US00D850254S

(12) **United States Design Patent** (10) Patent No.: **US D850,254 S**
Uetsuki et al. (45) Date of Patent: ** Jun. 4, 2019

(54) **CAP FOR CONTAINER**

(71) Applicant: **Kobayashi Pharmaceutical Co., Ltd.**,
Osaka-shi (JP)

(72) Inventors: **Hidetomo Uetsuki**, Osaka (JP);
Tomonori Shinkoda, Osaka (JP);
Satoru Komiyama, Osaka (JP)

(73) Assignee: **Kobayashi Pharmaceutical Co., Ltd.**,
(JP)

(**) Term: **15 Years**

(21) Appl. No.: **29/640,588**

(22) Filed: **Mar. 15, 2018**

(30) **Foreign Application Priority Data**

Sep. 15, 2017 (JP) 2017-020268

(57) **CLAIM**

The ornamental design for a cap for container, as shown and described.

DESCRIPTION

FIG. 1 is a perspective view of a cap for container showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken along line 8-8 of FIG. 7; and,

FIG. 9 is a cross-sectional view taken along line 9-9 of FIG. 7.

The broken lines illustrate structure or features which form no part of the claimed design.

1 Claim, 9 Drawing Sheets
